UNITED STATES PATENT OFFICE.

JOHN G. B. JOHNSON, OF PINE VALLEY, MANITOBA, CANADA.

WATER-GRAVE AND PROTECTOR.

967,128.

Specification of Letters Patent. Patented Aug. 9, 1910.

Application filed April 23, 1909. Serial No. 491,730.

To all whom it may concern:

Be it known that I, JOHN G. B. JOHNSON, a subject of the King of England, residing at Pine Valley, in the Province of Manitoba, 5 Dominion of Canada, have invented certain new and useful Improvements in Water-Tube Grates and Draft-Protectors. Therefor; and I do hereby declare the following to be a full, clear, and exact description of 10 the invention, such as will enable others skilled in the art to which it appertains to make and use the same.

The invention relates to a water tube fire grate and more particularly to the class of 15 stationary water tube fire grates with draft protector means therefor, designed for use in traction or other self propelled engines.

The primary object of the invention is the 20 provision of a grate of this character in which a series of spaced tubes are arranged in the same plane with each other and connected together at alternate ends so as to form a continuous flow of water therethrough when positioned in a fire box of a 25 traction engine or the like, and means connecting the grate with the water boiler to permit the delivery and discharge of water to the same.

Another object of the invention is the 30 provision of a water tube grate of the class described, in which the water tubes constituting the grate have connection with a boiler to enable a continuous flow of water through the said tubes, and means located beneath 35 the tubes of the grate to protect and shield the surfaces thereof that would necessarily be exposed to an air draft through the ash pit or beneath the grate.

A further object of the invention is the 40 provision of a water tube grate adapted for use with traction or other engines which is simple in construction, thoroughly efficient in operation and inexpensive and economical in the manufacture.

45 With these and other objects in view the invention consists in the construction, combination and arrangement of parts as will be hereinafter more fully described, illustrated in the accompanying drawings which 50 close the preferred form of embodiment of the invention and as brought out in the claim hereunto appended.

In the drawings:—Figure 1 is a front elevation of a boiler body and its fire box with 55 the invention applied thereto said boiler body being partly broken away. Fig. 2 is a

transverse sectional view through the fire box. Fig. 3 is a longitudinal sectional view. Fig. 4 is a horizontal sectional view on the line 4—4 of Fig. 1.

60 Similar reference characters indicate corresponding parts throughout the several views in the drawings.

In the drawings the numeral 5 designates generally the boiler body, having the usual 65 water chamber or boiler 6, riveted or otherwise secured at its forward end to a smoke chamber 7, and similarly connected at its rear end to a fire box 8, and leading from the latter to the smoke box through the wa- 70 ter chamber are a series of fire tubes 9, so as to permit the proper combustion of the fuel within the fire box.

Secured within the fire box to the lining 75 thereof are opposed supporting plates 10, upon which are adapted to rest alternately connected ends 11 of a plurality of spaced parallel water tubes 12, forming a fire grate 80 and which tubes are arranged in the same plane with each other to support fuel within the fire box. One extremity of the water tube grate has communication with the wa- 85 ter chamber 6, of the boiler by a discharge tube 13, and the opposite extremity of the fire grate projects through the front wall 14, of the boiler body and has connection through the medium of an elbow tube 15, with a vertical water supply pipe 16, the same having mounted therein a water ejector 17, having the usual connection (not shown) 90 with a suitable water supply pipe 18' and this ejector has communication with a steam inlet pipe 18 at the top of the body with the water chamber 6 therein, said ejector being adapted to supply a flow of water through 95 the water tube grate in the fire box. In the elbow pipe 15 is a check valve 19, to prevent the back flow of water in the supply pipe and the supply of water is controlled by an angle valve 20, mounted in the elbow pipe. 100

Suspended below the water tubes 12 are shields, each comprising a V-shaped plate 21, the latter being coextensive with the parallel portions of the tubes 12 and mounted transversely therein at intervals are cross pins 21' 105 the same resting upon the upper surface of the tube, whereby the said shields will be suspended immediately below the tube, so as to cover and protect the lower half of the water tube from an air draft created through 110 the fire pit or ash chamber 22 upon the opening of a draft door 23 of the usual type.

In this manner the water tubes 12 within the fire box are shielded or protected from being cooled by an air draft to effect the combustion of the fuel supported by the 5 grate within the said fire box.

From the foregoing description the construction and operation of the invention will be clearly apparent without the necessity of a further detail description or a more extended explanation therefore the same has 10 been omitted.

What is claimed is:—

The combination with a fire grate having spaced parallel water tubes, of V-shaped

plates disposed below the tubes and coextensive therewith, the said tubes being arranged within the plates, and transverse upwardly bowed pins disposed across the open tops of the plates at intervals and resting upon the upper surfaces of the said tube 15 whereby the said plates will be held suspended by the tubes.

In testimony whereof, I affix my signature, in presence of two witnesses.

JOHN G. B. JOHNSON.
